ABSTRACT: Wire stock is given an encircling, coaxial groove by shearing off a pair of slugs of material along equal and parallel chord planes on opposite sides of the wire axis, and pressing the remaining core of material in the direction of the chord planes first from one side and then the other to form the cylindrical surfaces of the groove. The shearing tool preferably includes a semicylindrical, concave die for forming half the groove surface in the shearing stroke, and a die with a slightly larger diameter semicylindrical surface presses from the opposite direction to complete the groove.

WIRE GROOVING METHOD AND MACHINE

THE IMPROVEMENT EFFECTED

Wire rods are used extensively as linkage and lever arms, and a preferred way to secure them in place is with spring clips snapped into encircling, coaxial grooves formed in the wire rods for this purpose. A familiar use of such rods is in carburetor linkages.

Previously, the retainer grooves in such rods have been cut by screw machines or machined with fixtures in processes that were relatively slow and costly. However, since groove formation has long required relative rotation between the work piece and a cutting tool, the screw machine process has been standard for grooving wire rods.

In an attempt to reduce the expense of groove cutting, opposed flat surfaces were formed in wire rods to receive the spring clip, but this has been rejected by the art because of the difficulty of assembly. A spring clip can be snapped onto opposed flat surfaces from only two directions, and this made assembly and reassembly especially difficult.

The objects of this invention include, without limitation, forming smooth, coaxial, cylindrical grooves of reduced diameter in wire by a punching operation that is faster, more efficient and less costly than previous groove-forming methods. Screw machines could groove and cut off wire pieces at about 12 per minute, and the inventive punching operation does this and other wire forming operations at a rate that has already reached 90 pieces per minute with prospects for increased rates in the future.

SUMMARY OF THE INVENTION

The inventive method includes: shearing a pair of slugs of material from the wire in the region of the groove along a pair of parallel, equal, chord planes on opposite sides of the axis of the wire, the distance between the chord planes being less than the diameter of the groove; pressing a first semicylindrical, concave die in the direction of the chord planes against the core material left between the chord planes to form the core material into a first semicylindrical surface of the groove; and pressing a second, semicylindrical, concave die against the core material in a direction opposite to the first die to form the core material into a second semicylindrical surface of the groove. Preferably the shearing tool includes the first semicylindrical die, which has a somewhat smaller diameter than the second semicylindrical die.

THE DRAWINGS

FIGS. 1-5 are partially schematic elevational views of the preferred tools shown in operational sequence for forming a wire groove according to the invention; and

FIG. 6 is an elevational view of a wire rod grooved according to the invention.

DETAILED DESCRIPTION

Throughout the specification and claims, the invention is described relative to formation of a groove in a cylindrical wire, the groove being a cylindrical section of reduced diameter coaxial with the wire. The inventive method and machine can also be used to form grooves in rod or stock material of a cross-sectional shape other than circular and to form a groove having a core or surface shape other than cylindrical.

Wire 10 shown in FIG. 6 has a groove 11 formed according to the invention. As shown in FIG. 5, groove 11 is smooth, generally cylindrical and coaxial with wire 10. The formation of groove 11 in wire 10 is shown in sequence in FIGS. 1-5.

In the first operation, tool 12 is driven against wire 10 as shown in FIGS. 1 and 2. Backup block 13 is arranged on one side of wire 10 and has a channel 14 of substantially the diameter of wire 10 for centering wire 10 relative to tool 12. Backup block 13 also has a slot for receiving tool 12, and passageways 15 communicate with such slot for carrying away slugs of material sheared from wire 10. Toolholder 16 holds

tool 12 and is driven in a reciprocal motion toward and away from backup block 13. A channel 17, also the diameter of wire 10, is formed in the face of toolholder 16 to assist in centering wire 10 relative to tool 12.

Tool 12 has an opposed pair of sharp shearing edges 18 and 19 spaced-apart by less than the diameter of wire 10, and somewhat less than the eventual diameter of groove 11. A semicylindrical sharp-edged die surface 20 connects shearing edges 18 and 19 at the back of the slot in tool 12 to form half the cylindrical surface of groove 11. Semicylindrical die surface 20 is formed with a diameter approximately equal to the distance between shearing edges 18 and 19.

As tool 12 is driven against wire 10 as shown in FIG. 2, shearing edges 18 and 19 shear off an opposed pair of slugs 21 and 22 of material from wire 10. Slugs 21 and 22 are drawn through passageways 15 by vacuum to keep them clear of tool 12. Because wire 10 is centered by channels 14 and 17 as it is struck by tool 12, shearing edges 18 and 19 are spaced equally on opposite sides of the axis of wire 10 so that the chord planes 23 and 24 along which slugs 21 and 22 are respectively removed, are approximately equal, parallel, and equally spaced on the opposite sides of the axis of wire 10.

As tool 12 is driven fully into wire 10, die surface 20 strikes the core of material between chord surfaces 23 and 24 to press such material toward the center of wire 10, and form it into the semicylindrical shape of die 20. The diameter of the resulting semicylindrical groove surface 25 is only slightly less than the ultimate diameter of groove 11.

For the sequence illustrated in FIGS. 3-5, wire 10 is preferably advanced to a second station to register the previously punched part of wire 10 with tool 28 that is held in toolholder 29 on the opposite side of wire 10 from tool 12 to face backup block 30. Centering channels 31 and 32 of the diameter of wire 10 are formed respectively across the face of backup block 30 and toolholder 29 to center wire 10 relative to tool 28. Toolholder 29 is driven toward and away from backup block 30 to advance tool 28 onto wire 10 in a punching operation.

Tool 28 has a notch 33 disposed to straddle chord surfaces 23 and 24 punched into wire 10, and a sharp-edged, semicylindrical die surface 34 is formed at the back of notch 33 in tool 28. As tool 28 is driven into a slot in backup block 30 as illustrated in FIG. 4, semicylindrical die surface 34 punches the core material between chord surfaces 23 and 24 toward the center of wire 10 to form such material into semicylindrical groove surface 35 as illustrated. Channels 31 and 32 center wire 10 accurately for such operation so that the semicylindrical surface 25 formed by tool 12 and the semicylindrical surface 35 formed by tool 28 are substantially coaxial to form the generally cylindrical surface of groove 11. Since the sides of notch 33 are slightly wider than shearing edges 18 and 19 of tool 12, tool 28 normally fits over chord surfaces 23 and 24, and the core material in the center of wire 10 moves under the impact of die 34 to form a smooth semicylindrical surface 35 blending evenly into the semicylindrical surface 25 previously formed.

FIG. 5 shows tool 28 retracted from backup block 30 to illustrate in cross section the ultimate shape of groove 11 relative to wire 10.

Passageways 37 are preferably formed in backup block 30 to communicate with the tool-receiving slot so that if any error in the advancement of wire 10 brings tool 28 into contact with an unpunched portion of wire 10, the slugs sheared from wire 10 by the edges of notch 33 will be received in passageways 37 and not harm tool 28 or backup block 30.

With retractable tools, it is possible within the spirit of the invention to combine all the operations illustrated in FIGS. 1-70 at a single station with a first shearing and punching stroke in one direction, retraction of this stroke, and a subsequent punching stroke from the opposite direction that is retracted to complete the operation without advancement of wire 10.

A variety of punch-type machines having reciprocating tools can be used to accomplish the inventive method, and

machine selection depends in part upon other operations that form the wire rod into a finished part. The inventive method has been successfully practiced on machines commonly known in the art as multislide or fourslide machines.

Persons wishing to practice the invention should remember that other embodiments and variations can be adapted to particular circumstances. Even though one point of view is necessarily chosen in describing and claiming the invention, this should not inhibit broader or related applications within the spirit of the invention. For example, the tools, toolholders and backup blocks can be arranged in a variety of ways for the inventive punching operation which can be accomplished in one, two, three or more stations as desired. Also, those skilled in the art will readily understand the adaptation of the inventive method of various known machines.

I claim:

1. A method of forming an encircling, coaxial groove in a wire, said method comprising:

- a. shearing a pair of slugs of material from said wire in the region of said groove;
- b. the shear planes for said slugs being two, parallel and substantially equal chord planes on opposite sides of the axis of said wire;
- c. the distance between said chord planes being less than the diameter of said groove;
- d. forcing a first semicylindrical, concave die in the direction of said chord planes against the core material between said chord planes to form said core material into a first semicylindrical surface lying substantially at the surface of said groove;
- e. forcing a second, semicylindrical, concave die against said core material between said chord planes in a direction opposite to said first die to form said core material into a second, semicylindrical surface lying substantially at the surface of said groove and communicating with said first semicylindrical surface to complete said groove surface.

2. The method of claim 1 wherein the diameter of said first semicylindrical die equals the distance between said chord planes, and the diameter of said second, semicylindrical die equals the diameter of said groove.

3. The method of claim 1 wherein said first semicylindrical die is formed as part of a tool for shearing said slugs so that said shearing and said first semicylindrical surface forming occur in a single stroke of said tool.

4. A machine for forming an encircling, coaxial groove in a wire, said machine comprising:

- a. a first tool;
- b. said first tool having a pair of shear edges spaced-apart by

- less than the diameter of said groove;
- c. said first tool having a semicylindrical, concave, die surface joining said shear edges;
- d. a first backup block having a channel for locating said wire;
- e. said first backup block being disposed on the opposite side of said wire from said first tool;
- f. a first holder for moving said first tool toward said first backup block to shear a pair of slugs of material from said wire in the region of said groove along a pair of shear planes that are parallel and substantially equal chord planes on opposite sides of the axis of said wire, and to force said semicylindrical, concave die against the core material between said chord planes to form said core material into a first semicylindrical surface lying substantially at the surface of said groove;
- g. a second tool having a slot the width of the diameter of said groove;
- h. said second tool having a semicylindrical, concave die surface connecting the walls of said slot;
- i. said second tool being disposed on the opposite side of said wire from said first tool;
- j. a second backup block having a channel for locating said wire;
- k. said second backup block being disposed on the opposite side of said wire from said second tool; and
- l. a second holder for moving said second tool toward said second backup block to force said second semicylindrical, concave die against said core material between said chord planes to form said core material into a second semicylindrical surface lying substantially at the surface of said groove and communicating with said first semicylindrical surface to complete said groove surface.

5. The machine of claim 4 wherein said first backup block is formed with openings for receiving said slugs of material.

6. The machine of claim 5 wherein said second backup block is formed with openings for receiving any material sheared from said wire by said second tool.

7. Punching equipment comprising:

- a. no change
- b. no chance
- c. a holder for punching said first tool against a workpiece in one direction and a holder for punching said second tool in the opposite direction against said punched region of said workpiece with said slot of said second tool aligned with the path of said slot of said first tool.

8. The punching equipment of claim 7 including a backup block disposed opposite each of said tools to support and locate said workpiece.
